United States Patent Office

Des. 224,762
Patented Sept. 12, 1972

224,762

SIGN

Ronald F. Gentzen, Tulsa, Okla., assignor to Lowrance Electronics Manufacturing Corporation, Tulsa, Okla.

Filed Sept. 28, 1970, Ser. No. 25,224

Term of patent 14 years

Int. Cl. D20

U.S. Cl. D96—12

FIG. 3

FIG. 2

FIG. 1

FIG. 1 is a front elevational view of a sign showing my new design.

FIG. 2 is an elevational view taken from one side thereof, the opposite side being the same as the side shown.

FIG. 3 is a rear elevational view thereof.

I claim:

The ornamental design for a sign, substantially as shown and described.
